UNITED STATES PATENT OFFICE.

VICTOR W. ZILEN AND RALPH E. FAIR, OF CHATTANOOGA, TENNESSEE, ASSIGNEES
TO LUCEY MANUFACTURING CORPORATION, OF CHATTANOOGA, TENNESSEE, A
CORPORATION OF TENNESSEE.

WELL-CASING WRENCH.

1,380,513.

Specification of Letters Patent. Patented June 7, 1921.

Application filed August 2, 1920. Serial No. 400,819.

To all whom it may concern:

Be it known that we, VICTOR W. ZILEN, a citizen of Russia, and RALPH E. FAIR, a citizen of the United States, both residing at 5 Chattanooga, in the county of Hamilton and State of Tennessee, have invented certain new and useful Improvements in Well-Casing Wrenches; and we do hereby declare the following to be a full, clear, and exact description of the same, reference being had to the accompanying drawings, forming part of this specification.

This invention relates to improvements in wrenches and more especially to that type of wrench adapted for screwing and unscrewing sections of well casing pipe or tubing. As is well known, wrenches for work of this character are necessarily of massive construction and are quite inconvenient to 20 handle and manipulate, considerable time being consumed, for instance, in applying and locking the wrench in position on a pipe section to be connected to or disconnected from another section.

One object of the present invention, therefore, is to provide a wrench that can be applied to a pipe and locked thereon with a minimum loss of time. A further object is to construct the wrench and its gripping 30 jaws so that they will take a bearing on the pipe throughout a major portion of the circumference of the pipe. In this way, deformation of the pipe, so frequently caused by wrenches making a point contact with the 35 pipe, is practically eliminated.

In the accompanying drawings:—

Figure 1 is a top plan view of a wrench embodying the present improvements;

Fig. 2 is a side elevation; and

Fig. 3 is a sectional view taken on the line 3—3 of Fig. 1.

The wrench of the present invention has a substantially circular head formed of two clamping or gripping jaws 10, 11, pivoted to 45 an operating lever or handle 12. As shown, the jaws 10, 11 are pivoted at points spaced longitudinally of the lever 12 so that movement of the lever in one direction will contract the jaws and cause them to grip a pipe or casing between them, while a movement in the opposite direction will expand the jaws and release the pipe. In order to prevent deformation of the pipe sections operated upon, the two jaws are formed with

curved gripping surfaces 13 substantially 55 conforming to the cross sectional contour of the pipe and when the jaws are contracted they engage the pipe throughout the greater portion of its circumference, the compression strains being evenly distributed over a 60 large area instead of being localized in one or two spots.

As wrenches of the type to which this invention relates are quite cumbersome and the sections of pipe used for well casing are 65 generally formed with collars at their ends, the present invention seeks to provide means whereby the clamping or gripping jaws of the wrench may be opened in order that the wrench may be readily applied to and re 70 moved from the pipe sections without the necessity of elevating the wrench above the upper end of the pipe section which usually projects a considerable distance above the ground. 75

With this object in view one of the jaws 10 is formed of a plurality of sections, preferably two, pivotally connected together by a pivot pin 15 and the outer end section 14 may be swung open on said pivot pin. The 80 other clamping jaw 11 is pivoted to the operating lever 12, as before mentioned, and it can likewise be swung open on its pivot pin. When both jaw 11 and the outer section 14 of jaw 10 are opened on their pivot pins a 85 pipe can easily be passed between them to a position where the jaws can again be closed.

To lock the jaws in their closed position, the free end of one jaw, preferably jaw 11, has a combined handle and locking latch of 90 a bell crank form pivoted by a pin or pintle 16 in ears 17 on said jaw, the latch member of the combined latch and handle being formed with a T-head 18 adapted to interlock with a pair of spaced lugs or hooks 19 on 95 the swinging end of the other jaw. When the parts are in closed position, as shown in Fig. 1, a spring 20, housed in a recess 21 in the combined latch and handle, yieldingly holds the T-head 18 in engagement with hooks 19 but when it is desired to open the wrench T-head 18 may be swung inward on its pivot pin by the handle 22, the central portion of the end of jaw 11 having a recess 100 therein to permit this movement of the T- head (see Fig. 3). In opening the jaws, handle 22 is used to disengage the locking elements 18 and 19 and to swing jaw 11 on 105

its pivot pin, a second handle 23 being formed on the outer section 14 of the other jaw to assist in opening that section.

The opening movement of the gripping jaws is limited by shoulders 24, 25 on jaw 11 and lever 12; shoulders 26, 27 on the two sections of jaw 10, and shoulders 28, 29 on the jaw 10 and lever 12 and the last mentioned shoulders 28, 29 also serve to limit 10 the lever movement when said lever is being moved around a pipe to expand the jaws.

In operation, the wrench is suspended in the space of the derrick by a rope or other suitable suspension means secured in a clevis 30 pivoted on the pivot pin of jaw 10 at one end of the lever, and a second rope or chain secured to the other end of the lever 12 through a hole 31, is connected to a suitable source of power. When two sections of pipe 20 are to be screwed together, the wrench assumes the position shown in Fig. 1, and is given a partial clockwise revolution by power applied to the outer end of lever 12 through the rope secured in hole 31. This 25 movement of the lever will cause the jaws to close upon and grip the pipe and impart a part revolution to the latter after which the lever is returned in a counter clockwise direction to its initial position by power applied to the lever through a rope connected to a clevis 32 located intermediate the ends of the lever. This return movement of the lever is preferably accomplished by hand, very little power being necessary as the jaws 30 are expanded and the pipe released, due to the location of the pivotal connections between the jaws 10, 11 and lever 12. These operations are successively repeated until the two sections of pipe are securely connected together. To disconnect two sections, the wrench is turned over and the motive power utilized for imparting the counter clockwise movement of the lever, as will be readily understood. The powerful grip 45 taken by the jaws on the pipe is due to the location of the pivotal connections between the jaws and lever, the relative positions of these pivotal points giving the requisite lever ratio for gripping the pipe. The tighter 50 the pipe is to be screwed in, or the tighter

the connection between two sections to be disconnected, the greater must be the force applied at the end of lever 12 and as this force is increased the gripping force or friction between the jaws and pipe will be correspondingly increased. 55

What we claim is:

1. In a pipe wrench, the combination of an operating lever, a pair of gripping jaws pivotally connected to the operating lever, 60 one of said jaws being formed of pivotally connected sections and having a handle formed thereon, and means for locking said jaws in closed position, said locking means comprising a catch formed on one jaw, a 65 pivot pin carried by the other jaw, a latch pivotally mounted on said pin, and adapted to engage said catch, and a spring surrounding said pin and engaging the latch for yieldingly maintaining said latch in engagement with the catch and a handle formed on said latch. 70

2. In a wrench, the combination of an operating lever, a pair of jaws pivotally connected to the lever, a catch formed adjacent the free end of one jaw, a handle formed on said jaw, a pair of ears formed adjacent the free end of the other jaw, a pivot pin carried in said ears, a latch pivoted on said pin, a spring secured within 75 the latch and engaging the latch to yieldingly maintain the latch and catch in locked position, and a handle formed on the latch. 80

3. In a pipe wrench, the combination of a pair of circularly arranged gripping jaws, 85 an operating lever adapted to radially expand and contract said jaws, one of said jaws being pivoted to said lever and the other jaw having a pivoted outer end section, whereby said pivoted jaw and end section may be swung open to permit insertion or removal of a pipe, a latch-catch on said pivoted end section, a latch carried by said pivoted jaw adapted to engage said catch, a handle on the pivoted end section, and a 90 handle on said pivoted jaw connected to said latch. 95
